UNITED STATES PATENT OFFICE.

SAMUEL JANKELSON, OF ROCKAWAY BEACH, NEW YORK, ASSIGNOR TO INCANDESCENT SUPPLY COMPANY, OF NEW YORK, N. Y.

DESIGN FOR A LAMP-SOCKET COVER.

52,057.

Specification for Design.

Patented May 28, 1918.

Application filed February 9, 1918. Serial No. 216,355. Term of patent 3½ years.

To all whom it may concern:

Be it known that I, SAMUEL JANKELSON, a citizen of the United States, residing at Rockaway Beach, Long Island, in the county of Queens and State of New York, have invented a new, original, and ornamental Design for Lamp-Socket Covers, of which the following is a specification, reference being

had to the accompanying drawing, forming part thereof.

The figure is a perspective view of a lamp socket cover showing my new design.

I claim:

The ornamental design for a lamp socket cover as shown.

SAMUEL JANKELSON.
